ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS

CAR DOOR

Application filed July 5, 1929. Serial No. 375,918.

This invention relates to improvements in car doors.

An object of the invention is to improve the construction of sliding car doors and more particularly that type of door used for automobile cars wherein large openings are provided and oppositely sliding doors employed.

It is an object of my invention to provide a double door construction wherein the auxiliary door is provided with a door post construction which will be strong and efficient and also provide adequate weatherproof points at the meeting edges of the doors.

Another and more particular object of my invention is to provide a door post construction of angular formation in a manner as to coordinate the strength of horizontally extending corrugations with the vertical strength of the door and thus effect continuity of reinforcement between horizontal corrugations and a vertical post member to prevent bending of the door on various cross-lines.

Other objects of the invention will be more clearly apparent from the description and claims hereinafter following.

In the drawings forming a part of this specification, Figure 1 is a side elevational view of a portion of a car showing my improvements incorporated therewith. Figure 2 is an enlarged broken side elevational view of the central portion of the doors shown in Figure 1. Figure 3 is a broken vertical sectional view taken through the doors shown in Figure 1. Figure 3 is a broken vertical sectional view taken through the doors and on a line corresponding substantially to the line 3-3 of Figure 2. Figure 4 is a broken horizontal sectional view, on an enlarged scale, corresponding substantially to line 4-4 of Figure 1. Figure 5 is a horizontal sectional view taken through the door post on the line 5-5 of Figure 3. Figure 6 is a horizontal, sectional view taken through the central portions of the doors and on a line corresponding substantially to the line 6-6 of Figure 2. And Figure 7 is a horizontal sectional view through the door post and corresponding substantially to the line 7-7 of Figure 3.

In said drawings, the car is shown as pro-

vided with a large opening adapted to be closed by oppositely sliding doors as indicated at A and B respectively, said door A being in the nature of a main door and adapted to be used for normal loading and unloading requirements, whereas door B is in the nature of an auxiliary door and is adapted for use only when a door opening of abnormal size is required. At the upper portion of the door opening, 10 indicates the usual top side plate of the car and is preferably of Z-shape formation, 11-11 the vertical door posts, of the car, 12 the lower sill of the car, 13 the car floor and 14 the threshold plate.

In the embodiment shown, the doors are of the bottom supported type and for this purpose a supporting track 15 is employed, said track being preferably of channel shape and supported by a series of brackets 16, the doors 70 being provided with supporting mechanisms C which rest upon the supporting track 15.

Adjacent the upper margins of the doors there is disposed the usual guiding track and weather guard 17 and adjacent the meeting edges of the doors there is disposed a weather shield 18 adapted to cover the meeting edges of the doors.

Both of the doors A and B are composed of metal, the main body portions being of relatively light gauge while the marginal reinforcing members are composed of relatively heavier gauge metal. The body portion of each door, preferably consists of three panels as indicated at 19, 20 and 21 for door A and 22, 23 and 24 for door B.

The respective doors A and B are of similar construction insofar as the upper horizontal, rear vertical and lower horizontal margins are concerned, but differ in features of construction relating to the meeting edges of the doors. Each door includes a top Z bar 25, and at the rear vertical margin a Z bar 26 having the inner flange modified to present a U-shape 27 adapted to engage in wedging relation with flange 28 extending from the associated door post structure 11. Said Z bars 25 and 26 are respectively secured to the door paneling by flanges 29 which overlie the metallic paneling. The front vertical margin 100

of door A includes a U-shaped member 30 having a transversely extending wall 31 defining the extreme outer edge of the door and walls 32 and 33 respectively disposed in substantially the inner and outer planes of the door framing, the depth of said framing being defined substantially by the depth of wall 31. Said outer wall 33 overlies the body paneling and is secured thereto by rivets 34. 10 The front vertical margin of auxiliary door B includes an angle shaped post member 35 having walls 36 and 37, respectively, extending in the plane of the door and transversely thereto, the former being secured to the body paneling of the door by two series of vertically extending rivets as indicated at 38 and 39 respectively. The transversely extending wall 37 is disposed adjacent the front edge of the door and when doors A and B are in 15 meeting relation, said wall forms an abutment for transverse wall 31 of the companion door. Cooperating with the walls 32 and 33 of door A on the respective outer and inner sides are the forwardly projecting walls 40 and 41, the former preferably consisting of a plate member secured to the outer face of door B by the series of rivets 38, said plate being offset slightly as indicated at 42 and extended outwardly beyond the transverse 20 wall 37 and into overlapping relation with door A; the inner wall 41 preferably consists of one wall of an angle shaped member 43 having the other wall 44 secured to that portion of the transverse wall 37 which extends 25 outwardly beyond the main door A, said wall 41 being flared at its outer end as indicated at 45 to facilitate the overlapping relation of the doors.

The bottom of each door is formed of generally tubular construction for the purpose of strengthening the doors. In providing the tubular formation, the lower edge of the lower door panel is deflected inwardly (Figures 3 and 4) as indicated at 46, and cooperating with the said panel is a facing plate 47 offset inwardly and secured to said panel by two rows of rivets as indicated at 48 and 49 respectively, the facing plate on door B being crimped at 50 and extended so as to overlap the flange 36 of the door post member and being secured thereto, the said flange 36 being preferably disposed on the inner side of the door.

There are preferably two roller mechanisms C per door each mechanism including a housing 51 having an axle 52 fixedly carried thereby and on which a roller 53 is rotatably mounted. Connections between the tubular formation and the webs of the vertical margins is effected on the inner side of the door by flanged corner gusset connections as indicated at 79.

The doors are further braced on the inner sides thereof by diagonally extending braces 54 having channel shaped portions 55, said

braces extending from the lower tubular section of each door to the respective front and rear vertical marginal elements, said braces having flanges adjacent their ends riveted to the marginal elements and adjacent portions of the lower tubular formation, and also having side flanges riveted to the paneling intermediate the corrugations as shown. The diagonal brace 54 which extends to the outer vertical reinforcement of the auxiliary door has its channel shaped portion offset as indicated at 56 to overlie the flange 36 of the post member.

Disposed in the angle presented by the respective walls 36 and 37 of the post member are a series of brackets as indicated at 57, 58, 59, 60 and 61, said brackets being secured to the walls 36 and 37 of the post member and to the body paneling by rivets. Said brackets are extended outwardly a limited distance beyond the end of the transversely extending flange 37 and each presents a wall 62 extending in the general plane of the door and spaced inwardly from the inner face of the door. Mounted on the walls 62 and rigidly bolted thereto by bolts 63 is a wooden nailing block 64 which is adapted to receive one end of a removable grain closure when the car is used as a grain car, said block preferably extending from top to bottom of the door.

Rotatably and slidably mounted in the brackets between the nailing block and the inner face of the door are upper and lower anchoring bolt members 65 and 66 adapted to respectively cooperate with socket members 67 and 68 for the purpose of locking the door relatively to the car structure. The upper bolt member 65 is mounted in brackets 57, 58, and 59, each of said brackets being provided with a circular opening, 69, within which the bolt extends. Bracket 57 is located adjacent the top of the door and bracket 59 adjacent the lower portion of the upper sliding bolt 65 and the latter bracket is provided with a ledge portion 70 adapted to cooperate with a laterally extending head 71 on the bolt, said cooperating ledge and bolt head being for the purpose of maintaining the bolt in projected locking position. The movement of the bolt head into and out of engagement is dependent on a partial rotation of the bolt-head whereby the bolt head is moved free of the associated ledge 70 and may then be moved longitudinally and disengaged from its associated socket member 67, said bolt when in inoperative position being supported by a bracket member 72 spaced a short distance below the ledge 70. The member 72 preferably consists of a short piece of commercial angle bar riveted to the door post. The member 65 when in operative locking position is maintained against rotation by the pin 171.

The lower bolt member 66 is mounted in the bracket 61, the latter being located ad-

5 jacent the lower edge of the door and disposed to overlie the outer end of the facing plate 47 and connected thereto and to the respective vertical walls 36 and 37 of the post member 35. The bracket 61 is formed with a ledge 73 adapted to engage the laterally extending head 74 of bolt 66 to maintain the bolt in retracted position. When the locking bolt 66 is projected into operative locking position the head 74 rests upon a shelf 75 formed integrally with the bracket.

10 The strengthening indentations in the body paneling include horizontal corrugations 76 which extend clear across the door 25 to reinforce the same intermediate the vertical margins. Said corrugations are disposed outwardly of the main body of the paneling and may be of any desired shape but preferably include flat crest and valley 26 portions as indicated at 78 and 77 respectively (Figure 3), the said flat crest portions 78 being preferably of greater width than the flat valley portions 77. Adjacent the forward vertical margin of the auxiliary door 25 B the said corrugations are extended into the plane of the overlying flange 36 and the strength of said corrugations is continued beyond the ends of the same by the said flange 36 as well as by the respective bracket 30 castings 57, 58, 59, 60 and 61. The latter by reason of their attachment to both flanges of the post member 36 thus provide continuity of strength from the central portion 35 of the door to the extreme end of the vertical post member and provide against bending of the door on horizontal and vertical cross lines. The construction of the doors, whereby the meeting edges of the doors are provided with transverse abutting walls of 40 considerable width in combination with inner and outer overlapping flanges, provides for a very efficient weather-proof joint at the meeting edges of the doors, and in addition provides for the impact of the meeting doors 45 to be taken on their edge portions, where such doors are formed of thicker material.

50 While I have herein shown and described what I now consider the preferred manner of carrying out my invention, the same is merely illustrative and I contemplate all changes and modifications that come within the scope of the claims appended hereto.

I claim:

55 1. In a door construction of the character described, the combination with a main sliding door and an auxiliary sliding door, said auxiliary door including a main body portion and a marginal reinforcing member secured to said door and having a transversely extending wall adapted to cooperate with the main door; of bracket members secured to said transverse wall and the body portion of the door and extended beyond said transverse wall; and a nailing block mounted on

and secured to said brackets independently of and beyond the end of said transverse wall.

2. In a door construction of the character described, the combination with a main sliding door and an auxiliary door, said auxiliary door including a main body portion formed of metallic paneling, and provided adjacent its forward edge with a post member of angular shape having one of its walls secured to the body portion of the door and having the other of its walls extending transversely of the door; of brackets disposed in the angle presented by said angularly related walls and directly secured in engagement with both walls; and a nailing block mounted on and secured to said brackets independently of the said post member, said nailing block being disposed inwardly beyond the transversely extending wall.

3. In a sliding door of the character described, the combination with a main body portion; of means associated with one edge of said door to provide an abutment for a second door, said means including a commercial bar member of angular formation having one flange extending transversely of the door and having the other flange overlying the body portion of the door and secured thereto; brackets in the angle of said bar member and secured to both flanges thereof; numbers presenting walls extending in the general direction of the door and projecting forwardly beyond said transversely extending wall and adapted to respectively overlie the inner or outer faces of the second door said members being secured to the respective flanges of the angle bar member and to the respective walls of the brackets.

4. In a door construction of the character described, the combination with a main door and an auxiliary door; of transverse end walls on the respective doors, said walls of the respective doors being adapted to meet in abutting relation when the doors are in closed position, one of said walls extending transversely of the door inwardly beyond the other wall; and an angle shaped member secured by one of its flanges to said portion of the wall which extends beyond the other wall, said last named angle shaped member having the other of its flanges projecting beyond its associated transverse wall and into overlapping relation with the companion door.

5. In a door construction of the character described, the combination with a main door and an auxiliary sliding door, said doors when in closed position being adapted to meet in abutting relation, said auxiliary door including a main body portion and a marginal reinforcing post member adjacent the outer margin of the door, said post member having angularly related walls, one of said walls

being disposed on the inner side of the paneling in overlying relation therewith and the other wall being disposed transversely of the door; reinforcing corrugations in the body paneling having their end portions extended into the plane of the overlying flange and secured to said flange by rivets positioned within the plane of the corrugations; and an overlying plate member adjacent the ends of the corrugations secured to the paneling and the overlying flange of the post member, said plate member being extended outwardly beyond the transverse wall of the post and in overlapping relation with the main door.

6. In a door construction of the character described, the combination with a main sliding door and an auxiliary door, said auxiliary door including a main body portion including metallic paneling; of a post member secured to the paneling on the inner side of the paneling, said post having a transversely extending wall adjacent the free edge of the door; bracket means disposed in the angle defined by said transverse wall of said door post and the metallic paneling of the door; a separate member secured to the outer face of the door and to said bracket means and adapted to extend across the plane of the main door when said doors are in closed position, said main door having an outer marginal member secured to the door paneling and to said bracket means and including a transversely extending wall, said last named transverse wall constituting the abutting member adapted to engage with the post on the auxiliary door.

7. In a door construction of the character described, the combination with a main sliding door and an auxiliary door, said auxiliary door including a main body portion formed of metallic paneling and being provided adjacent its forward edge with a post member of angular shape having one of its walls secured to the body portion of the door and having the other of its walls extending transversely of the door and inwardly beyond the main door, said main door when the doors are in closed position being adapted to abut the transversely extending wall of the

auxiliary door; of overlapping flanges carried by the auxiliary door and adapted to respectively extend inwardly and outwardly of the main door, said outer flange consisting of a flat plate member secured to the outer face of the door and flared to extend over the main door, and said inner flange consisting of an angle shaped member secured by one of its flanges to that portion of the transversely extending wall of the post member disposed inwardly beyond the main door, and having the other of its flanges overlying the inner face of the main door.

8. In a door construction of the character described, the combination with a main door and an auxiliary door, said auxiliary door having a main body portion including metallic paneling, said paneling having a series of horizontally extending corrugations formed therein; and a marginal reinforcing member of angular shape having one of its walls extending transversely of the door and having the other wall overlying the inner face of the door and secured thereto, said last named wall being extended to overlie the plane of the corrugations for an appreciable depth to cooperate with said corrugations in strengthening the juncture of said post and paneling.

9. In a door construction of the character described, the combination with a main door and an auxiliary door, said auxiliary door including a main body portion and a marginal reinforcing member having a transversely extending wall adapted to cooperate with the main door; of bracket members disposed adjacent the transversely extending wall; a nailing block carried by the brackets, said nailing block being spaced from the inner face of the door and beyond the transverse wall; and door anchoring means disposed within the space defined by the said block and the transverse wall, said anchoring means including bolts rotatably and slidably mounted in said brackets.

In witness that I claim the foregoing I have hereunto subscribed my name this 29th day of June 1929.

ARGYLE CAMPBELL.
